UNITED STATES PATENT OFFICE.

FRANKLIN A. ALGER, OF GRAND RAPIDS, MICHIGAN.

ARTIFICIAL BAIT.

1,182,442.

Specification of Letters Patent.

Patented May 9, 1916.

Application filed September 8, 1914. Serial No. 860,659.

To all whom it may concern:

Be it known that I, FRANKLIN A. ALGER, a citizen of the United States, and a resident of the city of Grand Rapids, in the county 5 of Kent and State of Michigan, have invented a certain new, useful, and Improved Artificial Bait, of which the following is a specification, which, taken in connection with the accompanying drawing, fully discloses a complete and operative embodiment 10 of the invention, such that others may understand the construction and operation of the same.

This invention is concerned with artificial 15 baits, particularly for use in casting, and it is the object of this invention to provide a bait of this character which may be used in waters in which weeds, grasses and the like are growing and which will be practically 20 free from trouble so far as the liability of the hooks catching on the weeds and the like are concerned, yet which will not be so guarded that the hooks are ineffective to hook and retain fish once they have struck at 25 the bait.

Furthermore the bait provided in this invention is durable and efficient, being formed of few parts not likely to break or get out of order as will appear upon understanding 30 being had of the construction illustrated in the drawings in which,

Figure 1 is a side elevation of my improved bait. Fig. 2 is a central longitudinal section thereof. Fig. 3 is a plan view 35 of the bait. Fig. 4 is a view from underneath said bait. Fig. 5 is a rear end view thereof.

Similar reference numerals refer to similar parts throughout the several views.

In the construction of the bait illustrated there is provided a body 1 of wood not subject especially to the action of water, for instance, cedar wood may be used, said body being rounded and tapered from its front 45 end toward the rear as best shown in the plan view, Fig. 3. The forward portion of the body is somewhat thicker than the rear portion there being formed an abrupt shoulder at 2 substantially midway the length of 50 the body and on the under side thereof at the junction of the portions of the body of different widths. Secured centrally of the

body on the under side and immediately back of the shoulder is a weight 3 which may be attached to the body by any suitable permanent fastening means such as the screw 4, the position of the weight being such that the center of gravity of the device is back of and below the actual central point of the body. It will be noted that this weight 55 is of greatest width where it lies adjacent the body tapering therefrom outwardly. A staple 5 is permanently attached at the front end of the body to which the line may be secured in use of the bait as will be clear. 60

To the under side of the body 1 at either side of the front end of the weight 3 are attached the screws 6 being driven into the body so that the heads are practically in the same plane as the underside of the thicker 70 portion of the body this leaving the shanks of the screws projecting downward a distance below the bottom of the thinner portion of the body. The eyes 7 of two hooks 8 are positioned to receive the shanks of said 75 screws 6, being loosely mounted thereon so that the hooks will have considerable freedom of movement and may readily move upward at their rear ends into the dotted line position shown in Fig. 1. Secured to the 80 under side of the body 1 at the rear edge thereof is a plate 9 of thin metal which has struck therefrom the ears 10 as shown to serve as bearings for the pivotal mounting 85 of the yokes 11, said yokes, two in number, being formed from wire into long U-shaped structures with the upper ends of the U's turned outwardly to seat in the bearings, said U-shaped members passing around the hooks 8 a distance back of their pivotal 90 mounts thereby supporting them against too far downward movement, it being designed that the points of the hooks shall normally lie immediately back of the rear end of the body as shown in full lines in Fig. 1. 95

In the use of my artificial bait, it is secured at the end of a line by attachment to the staple 5 and cast into the water, the line being reeled in the usual manner. It will be clear that by reason of the tapered front end and outwardly extending sides of the body toward the rear that as the bait is drawn through the water, any weeds or other slight obstructions will be pushed to 100

either side and will not approach the pointed ends of the hooks to be caught thereby. Also it will be seen that the pointed ends of the hooks positioned back of the rear end of the body will be guarded against weeds or other similar fouling elements and will not normally become entangled therewith. The thicker front portion of the body permitting the lower bottom plane of the lower side of 10 said front portion also serves as a protection against the weight, members 11 and the hooks becoming caught and entangled with weeds, it being apparent that as the bait is thrown into the water, its slightly greater 15 specific gravity causing it to sink and when it is reeled in, the position of the center of gravity causing the rear portion of the bait to drop lower than the front portion so that the body of the bait is inclined upwardly toward its front end as it is drawn 20 through the water. It will also be clear that the weight will always cause the bait as it strikes the water, to assume its proper position, that is, with the weight beneath the 25 body 1 so that the body will be properly positioned to guard the hooks against entanglement with weeds, grasses and the like. Furthermore the formation of the bait with its wide rear end will, as it is drawn over 30 the surface of the water, cause an eddy which will turn the hooks in toward each other directly back of the center of the body.

As the bait is drawn through the water, it 35 attracts the attention of fish, and on striking at the bait by the fish, if the hooks were held firmly in the full line position shown in Fig. 1, it would be practically impossible to hook the fish owing to the position of the hooks back of the body 1. But the hooks being 40 pivotally mounted, as the jaws close on the bait, the hooks will be elevated into the dotted line position shown in Fig. 1 and in position for easily hooking the fish. It will be noted that the rear portion of the bait is provided with a series of dots 12. These dots are 45 of bright colors and attract attention so that when the strike is made it is practically always at the rear end of the bait, the jaws of the fish closing on the bait and elevating the 50 hooks into hooking position. With a large fish, the jaws may engage in front of the yokes 11 but this is not material as the pivotal mount of such yokes readily permits the elevation not only of the hooks but of the 55 yokes also where if the yokes were rigid with the body the jaws of the fish might not be permitted to close sufficiently to cause the elevation of the hooks to proper position. Also from the tapered formation of the weight, 60 as the hooks rise, they are forced outwardly away from each other in this manner separating the hooks to form two distinct and separated devices for catching a fish at different portions of the mouth.

I have shown two hooks, but it is evident 65 that the number may be varied at will. Also various other minor changes may be resorted to without departing from my invention. The bait may be painted any desired color both for purposes of preservation of the 70 bait and for attracting fish. The invention is not limited to the precise structure shown but comprehends all modifications in structure falling within the scope of the appended claims defining the invention. 75

Having thus fully described my invention, what I claim as new and desire to secure by Letters Patent is,—

1. In an artificial bait, a body comprising a widened rear portion and tapered front 80 portion, and a pair of hooks pivotally attached to the underside of the body with their pointed ends normally lying a short distance back of the rear end of the body and in a plane below the upper surface of the 85 body and above the under surface thereof.

2. In an artificial bait, a body comprising a widened rear portion and tapered front portion, a weight secured to the under side 90 of the body, and hooks pivotally attached to the under side of the body at each side of the weight and opening upward, the pointed ends of said hooks normally lying a short distance back of the rear end of the body and between the upper and lower sides thereof 95 but movable above the upper side of the body.

3. In an artificial bait, a body comprised of a relatively thicker and pointed front portion and a thinner and widened rear portion, 100 an upwardly tapered weight attached to the underside of the body back of the thicker portion, a hook pivotally attached at either side of the weight to the underside of the body and extending back of the rear end 105 thereof, said hooks having the pointed ends thereof normally lying directly to the rear of the body spaced a short distance therefrom and below the upper side thereof, and pivotally mounted U-shaped yokes secured to 110 the underside of the body through which the hooks pass, substantially as described.

4. In an artificial bait, a body comprised of a widened rear portion and tapered front portion, a hook pivotally attached to the 115 under side of the body, and a pivotally mounted yoke embracing and supporting the hook and retaining it against downward movement with the pointed end thereof lying directly back of the rear end of the body 120 at a point between the upper and lower sides thereof.

5. In an artificial bait, a body comprised of a widened rear portion and tapered front portion, a weight secured midway between 125 the sides of the body and to the under side thereof, a hook pivotally attached to the under side of the body at each side of the

weight, and a yoke for each hook pivotally attached to the under side of the body at the rear portion thereof, said yokes supporting the hooks against downward movement beyond a predetermined position with the points thereof directly to the rear of the body and below the upper side thereof.

In testimony whereof, I have hereunto affixed my signature in the presence of two witnesses.

FRANKLIN A. ALGER.
